DEVICE FOR THE TRANSMISSION OF VIBRATORY ENERGY

Filed May 5, 1924

Inventor:
Henry C. Harrison,
by *E. W. Adams Atty*

Patented Mar. 27, 1928.

UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

DEVICE FOR THE TRANSMISSION OF VIBRATORY ENERGY.

Application filed May 5, 1924. Serial No. 711,044.

This invention relates to mechanical systems for transmitting vibratory energy and has for its object to improve the transmission characteristics of such systems.

5 As pointed out in my application Serial No. 668,801, filed October 16, 1923, for the undistorted transmission of multi-frequency energy waves, such as those of speech or music, through a mechanical transmission line, each portion of the line should have substantially the same characteristic impedance throughout the frequency range to be transmitted as the portions immediately preceding and following it. For convenience, it is preferable to construct the mechanical line so that it has a characteristic impedance substantially constant throughout the frequency range. In the application above referred to, there are disclosed several 10 types of loaded mechanical lines which may be incorporated in mechanical transmission systems to secure the desired impedance characteristic.

There is disclosed herein a loaded mechanical line which has high dissipative properties and is particularly adapted for use as a terminating network for a system which would otherwise have a non-uniform terminating impedance. As indicated in my application above referred to, such a line should have high dissipation or damping in order that a short length of line may have substantially the characteristics of an infinitely long line. I have found that an elongated body of vibration dissipating material, such as rubber, if properly proportioned, has the required characteristics of mass, elasticity, resistance, and dissipation, so that it may be given a desired characteristic impedance and so that a very short length of it will substantially simulate an infinite line. This mechanical line in its preferred form is similar to a continuously loaded electrical line, having its constants uniformly distributed throughout its length, as distinguished from a lump loaded line.

Another feature of the invention provides an improved supporting and balancing means for an armature in an electromagnetic

reproducing system whereby the restoring forces may be made to vary with the armature displacement in the same manner as the pull due to the steady magnetic field. The armature is supported on knife-edged pivots by a tension member through the axis of oscillation, one end of the tension member being secured by short stiff springs, and the balancing is accomplished by providing knee-shaped springs on each side of the pivot, the tension in the springs being adjusted by deforming them at the point of support.

The invention resides further in the structural arrangements set forth in the following description and claims taken in connection with the accompanying drawings in which

Fig. 1 is a front view, Fig. 2 a longitudinal sectional view, and Fig. 3 a transverse sectional view of one embodiment of the invention. Figs. 4 and 5 are detail views of the armature support. Figs. 6 and 7 are a front view and a longitudinal sectional view, respectively, of another form of the invention. Fig. 8 is a longitudinal sectional view of a modification of Fig. 2. Figs. 9 and 10 are a longitudinal sectional view and a transverse sectional view, respectively, of another form of the invention. Fig. 11 shows graphically the characteristics of the device of Figs. 9 and 10.

Referring particularly to Figs. 1, 2, 8 and 9, there is shown an electromagnetic phonograph reproducer or recorder having a permanent magnet 10. An electromagnet may, however, be used if desired. Secured to the magnet 10 are soft iron pole pieces 12, 13 and 14, 15, preferably laminated with bevelled ends, between which is pivotally supported an armature 17, tapered at each end to reduce its mass. The armature 17 is mounted on an elongated bar 20, preferably of a suitable aluminum alloy, and is provided with recesses 21 for receiving the knife-edged pivots 61 on a supporting member 60 secured to pole pieces 12, 13. The bar 20 is held on its pivots and the armature balanced, preferably by the resilient sup-

porting and balancing means shown in detail in Figs. 4 and 5, and described hereinafter. A pair of windings 24 and 25 are mounted coaxially with the armature between the pole pieces and are connected by leads 26 and 27 to a suitable electric circuit.

The bar 20 is turned downwardly at its outer end to form a stylus holder 29, in which is mounted a phonographic needle 30

- 10 in engagement with a record 32. The device may be used either as a recorder of speech and music or as a reproducer thereof. The arrangements shown in Figs. 1, 2 and 8, however, are preferably used as reproducers, the 15 preferred form of recorder being shown in Figs. 9 and 10.

At the end of the bar 20 opposite from the stylus holder is a thin plate 34 of aluminum or some light material, and in engagement 20 with the plate 34 is a rubber tube or cylinder 36 having a small longitudinal bore. A spring 38 within this tube is secured to the bar 20 and to a ball 40, which is slightly larger than the diameter of the bore, and by 25 means of a cord 42 or the like may be positioned at any desired point within the rubber cylinder for tensioning the spring and thereby holding the rubber cylinder against a plate 34. The end 28 of the bar 20 is 30 preferably rectangular in cross-section and slightly tapered, and the plate 34 is provided with a rectangular hole in which the end 28 is held by the tension of the spring 38 and the rubber tube 36. The rubber cylinder or 35 tube 36 is enclosed in a casing formed of channel-shaped members 45 and 43, and is preferably out of contact with the casing so as to avoid so far as possible friction at the surface of the rubber, which would interfere with the transmission of the vibrations 40 therethrough. By making the inside dimensions of the channel-shaped members 45 and 43 substantially larger than the diameter of the rubber cylinder or tube, usually no supports are required for the tube, but the tube 45 may, however, be supported its whole length by soft felt or cotton wrapping, as shown in Fig. 7, or at its outer end by a felt, a cotton or a sponge rubber ring as shown in Fig. 8. 50 For most cases, however, it is believed preferable to reinforce the tube 36 by a thin metal strip 35, as shown in Figs. 9 and 10. This will prevent the rubber line from sagging and making contact with the case intermediate its ends.

The rubber line herein described is analogous to a uniformly loaded electrical line. The general expression for the impedance of any mechanical network is

$$Z_n = \sqrt{\frac{r + j\omega M}{g + \frac{j\omega}{S}}}$$

where r is mechanical resistance per unit

length and corresponds to the electrical resistance, g is the mechanical conductance in a unit section of the line and corresponds to the dielectric conductance, or leakage, in the electrical case, M is the mass corresponding to electrical inductance, S is the elasticity per unit length corresponding to the reciprocal of the capacity in an electrical circuit.

In order that the velocities of the armature at all frequencies attenuate equally, these constants should have such values that

$$\frac{r}{S} = gM.$$

In other words, the conditions requisite for a mechanical line to have a pure resistance characteristic impedance are analogous to those requisite to an electrical network for pure resistance. The velocity of the armature corresponds to the current in an electrical circuit. By choosing a material such as will have the proper stiffness or elasticity, mass and resistance, the impedance may therefore be made independent of the frequency, in which case the velocity of the armature is a faithful copy of the mechanical force in the case of a reproducer or the electromagnetic force in the case of a recorder.

The rubber line should be of considerable length. At least it should be long enough to dissipate practically all the energy imparted to it before it is transmitted from one end of the line to the other and reflected back to the starting point. This is desirable since if a considerable portion of the transmitted energy is reflected back to the starting point, the reflected energy would be in phase for certain frequencies of the impressed vibrations and out of phase for other frequencies, in which case the line would have a variable impedance and hence would not respond with equal velocities to equal forces at all frequencies. If the material used for the line has a small rate of dissipation of motional energy, the line must be long, while if the material has a high rate of dissipation, the line may be short. Excellent results have been obtained by means of a cylindrical line of pure gum rubber nine inches long, one-half-inch outside diameter and one-quarter inch inside diameter. It is obvious however that other vibration dissipating materials than rubber might be used such as leather, felt, cork, spongy lead.

Figs. 6 and 7 show the application of the invention to an electromagnetic transmitter. The arm 56 in this case is connected by means of a rod 46 to the usual diaphragm 47. The rubber line 36 is in this case supported by a wrapping 48 of soft fabric such as cotton or felt, but it may be supported by any of the arrangements herein described. Although this arrangement may be used as a loud speaking receiver it is preferable when

so used to locate the arm 56 between the armature and the rubber line as in the case of the recorder shown in Fig. 9.

In Fig. 8, the rubber line is shown as gradually tapered from the arm 20. This taper may be reversed, depending upon the characteristics desired. The reproducer may be supported on a comparatively heavy metal block 50 by a yoke or U-shaped member 51 pivoted to the case 45 to permit vertical movement and to the block 50 to permit horizontal movement. This arrangement provides a convenient support for the recorder and the reproducer, rendering them portable and readily attachable to any standard type of talking machine.

In the modification shown in Figs. 9 and 10, the disc 34 is held snugly against the cylinder 36 by means of a strip 35 of aluminum or other suitable material extending the length of the cylinder. One end of the strip 35 is secured by a rivet or other suitable means to the bar 20 and the tube is secured in place by a pin 52. By slightly compressing the tube longitudinally, the proper tension is provided to hold the parts together. By arranging the strip 35 in a vertical plane, sufficient rigidity will be added to the line so that it will not sag and touch the casing. When additional loading is required, the tube 36 may be filled with comminuted material 53 of any desired mass. Small size lead shot has been found to give very satisfactory results. The end of the tube may then be sealed by any suitable means. Fig. 9 also shows the preferred arrangement for a recorder. The stylus bar 54 in this case is located between the armature 17 and the rubber line 36 and carries a cutting style 55. A micrometer screw 57 attached to the recorder rests on the record 58 for gauging the depth of the cut in the record.

The preferred arrangement for supporting and balancing the armature is shown in Figs. 4 and 5. The supporting member 60 carries the knife edges 61 which engage the recesses 21 and the bar 20 to which the armature 17 is attached by any suitable means. The bar 20 is held on its knife-edge pivots by a thin rod 62 extending through the mounting 60 and the bar 20. One end of the rod 62 is secured to the mounting 60 by means of a plate 63, which has two opposing lugs 64 and 65 sheared from the plate. These lugs are bent outwardly and act as springs and engage the head 66 of the rod 62. The opposite end of the rod 62 projects through the bar 20 and is threaded for a nut 67 to adjust the tensioning rod 62 and the springs 64 and 65. For balancing the armature in the steady magnetic field, resilient members 68 and 69 are attached to the bar 20 on each side of a pivot. Members 68

and 69 are flat knee-shaped springs being given a slight bend or initial set, as shown at 70 and 71. Their opposite ends are secured to the mounting 60 by means of the U-shaped member 63 and rod 62. The bends 70 and 71 should be of a sufficient angle to permit maximum displacement of the armature before members 68 and 69 become straight. The mounting 60 is provided with transverse slots or grooves 72 and 73, into which the springs may be deformed under the pressure of nuts 74 and 75 to regulate the tension therein and effect a balance of the armature in the magnetic field.

Fig. 11 shows curves comparing the characteristics of recorders with and without the rubber line of the invention. The curves are plotted with velocity in transmission units as ordinates and frequency at constant driving current as abscissæ. A transmission unit is defined by the relation.

$$N = 20 \log_{10} \frac{V_1}{V_2}$$

where V_1 is the input velocity and V_2 is the output velocity, and N the number of transmission units by which the velocities V_1 and V_2 differ. Curve A is a typical curve showing the characteristic of an improved type of damped recorder. It will be noted that although damping was applied in this case, there is a decided resonance peak at a frequency within the audible range. B is a typical curve of a recorder provided with the rubber line of the invention. The response in this case is substantially uniform throughout the audible range and the efficiency has been substantially raised particularly at each end of the audible range.

It is obvious from curve B that a recorder embodying the invention is particularly suitable for recording renditions from an instrument or a group of instruments as it is capable of faithfully recording both the high and low frequency notes and also the harmonics characteristic of the different instruments. For natural reproduction of recording, it is quite important that the harmonics be faithfully recorded and reproduced in order that the individual instruments may be identified. In the usual type of reproducers, these harmonics are insufficiently registered to make it possible to clearly identify the recording instruments.

While the invention has been illustrated as applied to electromagnetic recording and reproducing devices it is obvious that it may be applied with advantage to microphone transmitters, the usual mechanical reproducers and recorders, oscillographs or any mechanical vibrating system.

What is claimed is:

1. A solid medium for receiving and dissipating vibratory energy comprising an elong-

- gated body of non-metallic vibration absorbing material of a homogeneous character, said body having precomputed values of mass, elasticity, resistance and dissipation per unit length such that the characteristic impedance of said body is substantially constant throughout a range of frequencies to be transmitted.
2. A solid medium for receiving and dissipating vibratory energy according to claim 1 in which said mass, elasticity, resistance, and dissipation are uniformly distributed throughout the length of said body.
3. In a line for the transmission of vibratory energy, a terminating portion comprising an elongated body of vibration dissipating material, and means for torsionally vibrating said homogeneous body.
4. In a line for the transmission of vibratory energy, a terminating portion therefore comprising an elongated homogeneous body of vibration-dissipating material having a characteristic impedance substantially equal to that of said line throughout a range of frequencies to be transmitted.
5. The combination of claim 4 in which the vibration dissipating material is soft rubber.
6. In an electromagnetic device, a vibratory armature, and an elongated solid body of vibration dissipating material adapted to be torsionally vibrated by said armature.
7. In an electromagnetic device, an armature, means for pivotally supporting said armature, an elongated homogeneous body of vibration dissipating material, the axis of said body being in alignment with the axis of oscillation of said armature and means securing said body to said armature for rotation therewith.
8. In an electromagnetic system, an armature, an elongated member receiving torsional forces from the vibration of said armature, a mechanical line of a homogeneous material having a high degree of dissipation connected to the end of said member remote from said armature, and a recording stylus connected to an intermediate point on said member.
9. The combination of claim 8, in which said mechanical line comprises an elongated body of rubber.
10. In a system for the transmission of mechanical vibratory energy, an elastic member, means for producing torsional vibrations in said member, an elongated body of rubber, and means for securing said body to said member in longitudinal alignment therewith.
11. The combination of claim 10, in which said body of rubber is in the form of a tube.
12. The combination of claim 10, in which said body is in the form of a tube, and said securing means lies within said tube.
13. The combination of claim 10 in which said body has a characteristic impedance substantially equal to that of the mechanical system to which it is secured.
14. In an electromagnetic device, a magnet, an armature disposed in the field of said magnet, a knife-edge support for pivotally mounting said armature, a tensioning rod to hold said armature on its pivots, and separate tensioning means to balance said armature in the field of said magnet.
15. The combination of claim 14 wherein two flat knee-shaped springs are provided for balancing the armature in the magnetic field, and means for deforming the ends of said springs to vary the tension.
16. The combination of a magnet, an armature in the field of said magnet, an oscillatory bar supporting said armature, a mounting for said bar, a soft rubber cylinder attached to the end of said bar and coaxial therewith, and a pair of springs attached to said rod, said rubber cylinder and springs adapted to control the vibrations of said armature.
17. In an electromagnetic device, a pivoted armature, a mounting for said armature, means for supporting said armature on its pivots, said means comprising a thin flexible rod extending through the axis of support of said mounting, and a short spring transverse and engaging said rod to yieldingly maintain said rod under tension.
18. The combination according to claim 17, in which two short springs engage said rod to yieldingly maintain it under tension.
19. An electromagnetic device according to claim 17, in which the rod is secured between the ends of said springs.
20. An electromagnetic system comprising an armature, a bar supporting said armature, a mounting pivotally supporting said bar, tensioning means securing said bar on its pivots, a pair of springs extending from said armature support to said mounting, and means for distorting said springs transversely to vary the tension in said springs for effecting a balance of said armature.
21. In an electromagnetic system comprising an armature, a bar supporting said armature, a mounting provided with a knife edge, a rod having one end associated with said bar, and a short spring extending transverse said bar and engaging the other end of said rod to exert tension therein and hold said bar upon its mounting.
22. In an electromagnetic device, a magnet, an armature in the field of said magnet, a bar supporting said armature, a mounting for said bar and armature, a pair of tensioning members connecting said bar and said armature, said tensioning members having a slight set, and means for separately adjusting the ends of said tensioning

members to effect a change in tension whereby the armature may be balanced in the magnetic field.

23. The combination of the electromagnetic device of claim 22 and a rubber line connected to the end of said bar for controlling the vibrations thereof.

24. In a line for the transmission of vibratory energy, an oscillatory member, an

elongated body of non-metallic vibration absorbing material forming a longitudinal extension of the axis of said oscillatory member and adapted to be torsionally vibrated thereby.

In witness whereof, I hereunto subscribe my name this 2 day of May A. D., 1924.

HENRY C. HARRISON.
